PURSE STRUCTURE

Otto Kominik, New York, N. Y.

Application May 22, 1943, Serial No. 488,069

3 Claims.

(Cl. 150—37)

This invention relates to purse structures, and in particular to coin holders.

Coins, preferably of small denominations, were heretofore carried in coin holders arranged therein either independently or in contact with one another and in superposed position and were held in place therein by means of metal springs formed so as to embrace or surround the rim or another part of the coin, or to press said coins together and against an abutment plate.

The purse or coin holder according to this invention is devoid of any metal springs and tends to overcome many disadvantages inherent in the structure of auxiliary spring means for releasably holding coins in a coin receptacle or compartment thereof.

It is one of the main objects of this invention to provide a purse or coin holder which may be manufactured from leather, relatively stiff cellulose material and the like and which requires substantially no metal parts for its function and practical use.

It is another object of the present invention to provide a purse of the aforesaid type which is inexpensive to manufacture, simple and compact in construction and in which coins are conveniently and clearly arranged for being grasped and manipulated by the fingers of one hand only.

It is a further object of the present invention to provide a coin holder which is light in weight, aesthetic in form and appearance, and which permits ready grasping and withdrawal of the coins therefrom although the same are held in firm engagement therein.

It is a still further object of the invention to provide a purse of the above nature which has separate compartments for receiving therein individual coins, if desired of different denominations, the walls of each compartment being so shaped and biased that the surface and periphery of each coin tightly and frictionally contact the respective walls of each compartment when inserted therein.

Yet, another object of this invention is to provide a purse structure made from relatively flexible, thin and friction providing material in layer formation, the layers being held in position by fastening means which at the same time constitute the lateral confines of each compartment of said purse.

These and other objects and advantages of the invention will appear from the following disclosure thereof together with the attached

drawing which illustrates a certain form of embodiment thereof. This form is shown for the purpose of illustrating the invention since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the drawing:

Fig. 1 is a plan view of one embodiment of this invention showing a circular coin holder, parts thereof being broken away.

Fig. 2 is a sectional view taken along line 2—2 of Fig. 1.

Fig. 3 is a plan view of a modified coin holder made in accordance with this invention.

Fig. 4 is a perspective view of a coin holder incorporated in a case and made in accordance with this invention.

Fig. 5 is a sectional view of the coin holder illustrated in Fig. 4, the section being taken along one coin compartment and a staple confining another compartment.

Figs. 6 and 7 show fragmentary views of an internal part of the circular coin holder of Fig. 1 in two different stages.

In that embodiment of the invention illustrated in Figs. 1 and 2, there is indicated by numeral 15 a circular and flat coin holder made from several layers of leather or similar relatively stiff, but yieldable and friction-producing material.

Coin holder 15 is provided with a number of cut-outs or notches 16 and of rounded projections 17 forming the remaining portions of said layers at their outer boundary. The coin holder 15 comprises the inner layers 19, 20 which are attached or fixed together by means of staples 18 arranged in circular row and position, as indicated in Fig. 1. On the upper and lower faces of joined layers 19, 20, there are provided respective top layers 21, 22 which are adhesively or otherwise united respectively to faces of said joined or stapled inner layers, thereby covering the latter and concealing said staples 18. It is to be understood that all layers are preferably coextensive with one another and are of congruent or corresponding shapes.

It will be realized from Figs. 1 and 2, that pockets 25 are provided which radially extend between said inner layers from each notch 16, the depth of each pocket being determined by

two adjacent staples 18, each pocket serving for the purpose of receiving a coin 23.

Due to this construction, each coin is held very tightly and with friction flatwise and independently in the respective pocket whose walls upon insertion of the coin have the tendency to slightly bulge, as indicated at 24.

Due to the fact that according to this invention differently grained leather layers may be held together in their assembled condition, any stretch imparted to the leather layers during the insertion of each coin is substantially maintained, but is then compensated for upon withdrawal or removal of the respective coin.

The leather layers may also be biased in a different manner so as to overcome the consequences resulting from stretches exerted when coins are being inserted in the pockets of the coin holder. To this effect, the inner layers may be provided with a cut-out 61 (Figs. 6 and 7) intermediate adjacent notches 16 at inner layer 60 and its adjacent layer, which both layers are then joined by staples 62, 63, contracting portions of said inner layers at the location of said staples or joining means 62, 63 thereby obtaining a predetermined bias or compression of the pocket walls formed by the inner layers toward each other which in turn are thereafter covered by outer layers, as described in connection with coin holder 15 of Fig. 1.

Fig. 3 shows a modified coin holder which is similar in construction to that of Fig. 1. Coin holder 30 has differently shaped notches 31 and differently shaped projections 32 providing therebetween respective pockets for insertion of coins 34, the pockets being laterally confined by staples 33. Coin holder 30 is adapted to hold coins of different denominations, such as pennies, nickels, dimes and quarters.

Figs. 4 and 5 show the application of the invention to several coin holders 41, 42 associated with a case 40. Coin holders 41 and 42 are hingedly and swingably connected at 43, 44 to the inner face 45 of the flaps 46, 47 of case 40. Layers 41a and 41b are made up similar to inner layers 19, 20 of coin holder of Fig. 1, are connected together by staples 50a and have the outer or covering layers 41c, 41d and are provided with notches 48 forming the open ends of respective pockets which are laterally confined by means of spaced staples 50a. It is well understood that coin holder 42 corresponds to the shape, construction and function of coin holder 41. Case 40 has the snap fasteners 51, 51a, the latter being positioned on flap 52 which is swingably connected to the base flap 47 of case 40.

By manipulation of the snap fasteners 51, 51a case 40 may be closed.

It is well understood that the center portions of the inner layers may be adhesively or otherwise connected together in order to give body to the structure. It can be further easily realized that additional layers having smaller diameters can be built up on the coin holder of Fig. 1 which may be used, for instance, for holding dimes or coins of other denominations, the structural features being always based on the same conception of this invention.

It can thus be seen that there has been provided in accordance with this invention a coin holder of the character described which comprises a structure of layers, inner layers and outer layers, respectively, said layers being made of yieldable but relatively stiff material, such as leather, spaced apart notches provided at the 75

outer boundary of said layers and inwardly extending therefrom, projections intermediate said notches, and spaced apart fastening or attaching means, such as staples, joining the inner layers together and disposed at said projections of said inner layers whereby single compartments are formed therebetween, each of said compartments providing an opening along the contour of a respective notch and between adjacent parts 10 of said inner layers which form the walls of said compartment, each of said compartments being confined by two adjacent of said staples which may form lateral abutments for a coin when inserted in a respective compartment, the outer 15 layers covering said staples and said joined inner layers and being connected to the latter to reinforce said structure, said coin being concealed in said compartment and extending to said boundary within said notch for gripping 20 engagement by the fingers of a hand.

While there has been shown and described and pointed out the fundamental novel features of the invention as applied to the above embodiments, it will be understood that various omissions and substitutions and changes in the form and details of the device illustrated and its operation may be made by those skilled in the art without departing from the spirit of the invention.

30 Having thus described the invention what is claimed as new and desired to be secured by Letters Patent, is:

1. A purse for holding coins comprising a plurality of coextensive superimposed layers of 35 yieldable, but relatively stiff and friction-producing material forming together a unitary structure of inner layers and outer layers, all layers being provided at their outer boundary with coextensive inwardly extending spaced apart 40 notches, spaced apart attaching means for joining said inner layers to each other at locations positioned adjacent and laterally of said notches, whereby pockets are formed each having an opening along each notch and between adjacent 45 parts of said inner layers, each of said pockets being laterally confined by two adjacent attaching means, said outer layers covering said joined inner layers and being connected thereto to reinforce said structure, said attaching means laterally confining a pocket being spaced a predetermined distance to limit the depth of each 50 pocket for the reception of a coin, when inserted in one of the pockets, said coin being concealed in said one pocket and extending to said boundary for gripping engagement by the fingers of a hand of a person.

2. A purse for holding coins comprising a plurality of coextensive inner layers and outer layers, said inner layers being made of yieldable, friction-producing material and forming together with said outer layers a unitary structure, all said layers being provided at their outer boundary with inwardly extending coextensive notches, said notches being spaced from one another by the remaining portions of said layers at their outer boundary, and means joining said inner layers to each other in superposed relation and at locations positioned adjacent said remaining portions of said inner layers between said notches thereof, whereby pockets are formed between said inner layers, each pocket having an opening along the contour of each notch and being laterally confined by said joining means provided on two adjacent of said locations, said outer layers covering said joined inner layers and

being connected thereto to reinforce said structure, said joining means pressing portions of said inner layers at said locations toward each other, thereby increasing the friction upon a coin when inserted in a respective pocket, said joining means being spaced apart a predetermined distance to limit the depth of each pocket.

3. A purse for holding coins comprising a plurality of coextensive inner layers and outer layers, said inner layers being made of yieldable, friction-producing material and forming together with said outer layers a unitary structure, all said layers being provided at their boundary with inwardly extending coextensive notches, said notches being spaced apart from one another by the remaining portions of said layers at their outer boundary, each of said remaining portions of said inner layers being provided with

5 a radially extending cut-out, staples bridging said cutouts and joining said inner layers to each other in superposed relation and at locations positioned adjacent said remaining portions of 10 said inner layers between said notches thereof, said staples maintaining the adjacent edges of the cutouts in contacting relation to contract said inner layers and compress said inner layers toward each other, pockets being formed between said compressed inner layers, each pocket having an opening along the contour of each notch and being laterally confined by said staples, said outer layers covering said inner layers and being connected thereto to reinforce said structure, and said staples being spaced apart a predetermined distance to limit the depth of each pocket for the insertion of a coin therein.

OTTO KOMINIK.
